[57] CLAIM

The ornamental design for a golf bag with multiple satchels, as shown.

DESCRIPTION

FIG. 1 is a right side view of a golf bag with multiple satchels showing my new design;

FIG. 2 is a left side view thereof;

FIG. 3 is a front view thereof;

FIG. 4 is a rear view thereof;

FIG. 5 is a top plan view thereof; and,

FIG. 6 is bottom plan view thereof.

The crosshatch surface shading shown in all views is understood to repeat throughout the indicated area.
